UNITED STATES PATENT OFFICE.

GEORGE W. BIDWELL, OF NEW HAVEN, CONNECTICUT.

DESIGN FOR A CLOCK-DIAL.

SPECIFICATION forming part of Design No. 16,733, dated June 15, 1886.

Application filed November 30, 1885. Serial No. 184,372. Term of patent 7 years.

To all whom it may concern:

Be it known that I, GEORGE W. BIDWELL, residing at New Haven, in the county of New Haven and State of Connecticut, have invented and produced a new and original Design for Clock-Dials; and I do declare the following to be a full, clear, and exact description of the same, reference being had to the accompanying drawings, which form a part of this specification.

In the accompanying drawings, Figure 1 is a view in front elevation of a clock-dial embodying my design, and Fig. 2 is a similar view of a modification thereof.

The leading feature of my design is a clock-dial having an elliptical or substantially elliptical boundary outline and provided with characters concentric or substantially concentric with the said outline.

A is a dial having an elliptical boundary outline and provided with characters concentric with such outline, the longest axis of the ellipse passing through the characters III and IX, and the dial being wrinkled or corrugated in lines parallel with such axis.

C is a flat rectangular dial-plate, provided

with a dial, D, having an elliptical boundary outline and numerals concentric with such outline.

What I claim is—

1. The new and original design for a clock-dial shown and described, the same consisting of a dial whose boundary outline is of elliptical or substantially elliptical form and provided with characters concentric or substantially concentric with the said outline, as set forth.

2. The new and original design for a clock-dial shown and described, the same consisting of a wrinkled or corrugated dial whose boundary outline is of elliptical or substantially elliptical form, and which is provided with characters concentric or substantially concentric with the said outline.

In testimony whereof I have signed this specification in the presence of two subscribing witnesses.

GEORGE W. BIDWELL.
